PEN POINT CLEANER

Adolph B. Wikstrom, Los Angeles, Calif., assignor
of one-half to Meyer Egilson, Los Angeles, Calif.

Application September 16, 1947, Serial No. 774,324

2 Claims. (Cl. 120—108)

1

This invention relates to a device for cleaning pen points of the type that is used in writing, drafting, drawing or similar arts.

An object of the invention is to provide a device of this character having two rotating inter-engaging members which are adapted to receive the pen point therebetween, and clean all excess fluid from the pen point as it is engaged and disengaged from the members.

Another object of the invention is to provide a device of this character that is attractive in design and is equipped with means for holding the pen point after it has been cleaned.

With the above and other objects and advantages in view, the invention consists of the novel details of construction, arrangement and combination of parts more fully hereinafter described, claimed and illustrated in the accompanying drawings in which:

Figure 1 is a top plan view of an embodiment of the invention;

Figure 2 is an elevational peripheral edge view of the device;

Figure 3 is a sectional view on the line 3—3 of Figure 1;

Figure 4 is a sectional view on the line 4—4 of Figure 1;

Figure 5 is a detailed elevational view of the pen cleaning mechanism with the base broken away and

Figure 6 is a sectional view on the line 6—6 of Figure 5.

Referring more in detail to the drawings, the pen point cleaner assembly embodying the invention is generally designated by the reference numeral 10. The assembly 10 comprises a circular base 11 having an ornamental marginal edge 12 and a circular recess 13 in the center thereof. Formed on the base in upstanding relation thereto is the ring shaped flange 14 which is externally threaded at 15 to engage the internal threads 16 of the disk shaped top or cover 17. The marginal edge 18 of the top or cover 17 is ornamented to conform or harmonize with the ornamental edge 12 of the base 11.

Mounted on the upper surface of the top or cover 17 is an ornamental block 19 which, as shown, is substantially elliptical in shape, or it may be any shape desired. The center of the block 19 is provided with an opening 20 which is adapted to receive a pen point as shown by dotted lines in Figure 4.

Fasteners 21 and 21' are used to retain the block on the top or cover 17, and passing through the top or cover 17, the heads of the fasteners

are exposed on the undersurface of the top or cover.

The fastener 21, by means of its head, retains a spring catch 22, while the head of the fastener 21' retains the keeper 23 in place.

The catch 22 and keeper 23 are adapted to removably engage the horizontally extending rim flange 24 of the rectangular shaped frame 25. The frame, at one end, has a short pin shaft 26 rotatably mounted in the sides of the frame, transversely thereof, and cotter pins 28 in the shaft are positioned on opposite sides of the roller 29 to fix the roller on the shaft 26. The pins 28 engage the washers 30 abutting the sides of the roller 29 and the roller 29 is provided with a curved face 31. The curved face 31 of the roller 29 engages the annular groove 32 formed in the face of the roller 33, and both rollers are made of an ink absorbent material.

The roller 33 is fixed to the pin shaft 34 by cotter pins 35 in the shaft and washers 36 are placed in contact with the sides of the roller 33.

Due to the soft material from which the rollers are made, the washers are used to prevent the cotter keys from wearing into the sides of the rollers to permit the rollers to become loosened on their respective shafts.

The shaft 34 is rotatably mounted transversely of the frame 25 in the elongated slots 37 formed in the sides thereof. This mounting is provided so that a pen point can be inserted between the rollers, as will be later described. Loosely mounted on the ends of the shaft 34 is the yoke 38 on which is formed the apertured ear 29. The ear 39 is adapted to receive one end of the compression spring 40, the other end of which is received in the apertured ear 41 formed on one end of the frame 25. Thus the compression of the spring 40 urges the yoke toward the end of the frame on which the ear 41 is formed, and the yoke, in turn, urges the roller 33 into engagement with the roller 29.

Thus when a pen point is inserted between the rollers, the rollers will separate sufficiently to allow the pen point to be received therebetween, while at the same time engaging the pen point to clean the point of all excess fluid thereon.

Secured to the upper surface of the top or cover 17, by any well known fastening means, is a holder 42 of conventional, yet attractive, design, which is adapted to hold the pen point when inserted in a pen holder in the customary manner.

There has thus been provided a pen point cleaner which is attractive in design and will effectively clean a pen point when the pen point is

positioned between the rollers, as previously described.

The frame 25 and its component parts being made removable, can be replaced when the rollers are useless or the rollers only may be replaced as desired.

It is believed that from the foregoing description, the construction and operation of the device will be apparent to those skilled in the art, and it is to be understood that changes in the minor details of construction may be resorted to, provided they fall within the spirit of the invention and the scope of the appended claims.

Having thus described the invention, what is claimed as new and desired to be secured by Letters Patent is:

1. A device of the character described, comprising an ornamental base, an ornamental cover secured to said base, an opening in said cover to receive a pen point, a rectangular shaped frame mounted on the cover below the opening, said frame having aligned openings in the sides thereof and elongated aligned slots in the sides thereof spaced from each other in parallel relation to each other, a shaft journalled in the openings, and a shaft journalled in the slots rotating absorbent means mounted on the shafts in the frame

on the cover below the opening to clean a pen point when the pen point is inserted into the opening to engage the absorbent means and tensioning means connected to the shaft in the slots for urging the absorbent means on the shaft into engagement with the absorbent means on the shaft in the openings.

2. The invention as in claim 1, wherein the absorbent means comprises two rollers, the faces of which are adapted to engage with each other and at the same time conform in their engagement with the shape of the pen point.

ADOLPH B. WIKSTROM.
